GARMENT SUPPORTING AND DISPLAY DEVICE

Abraham Beckelman, New York, N. Y.

Application July 8, 1950, Serial No. 172,750

15 Claims. (Cl. 223—68)

1

My present invention relates generally to display forms for wearing apparel, and has particular reference to a collapsible and expandible form capable of supporting an article of apparel in flat hanging condition or in extended display condition as if worn by a model.

Ordinary hangers for supporting garments such as coats, suits or dresses cause the article of apparel to hang in an unnatural, unattractive manner without exhibiting to best advantage its form and appearance when it is worn on the human body. The display of articles on such hangers does not always contribute to their attractiveness or saleability. Expandible hangers are known which comprise a bar of common type together with a pivoted wire mechanism which is rotatable out of the plane of the bar to belly out the garment at the chest. These hangers cause the garment to occupy three dimensions rather than two, but they are objectionable in that even when expanded they merely support the garment along an additional line or two without really enhancing the resulting effect. When thus displayed, garments tend to crease at the wire contact lines and to fall into flat planes rather than into life-like curvatures.

It is a general purpose of my invention to obviate these objections by providing a display device which is able not only to support garments for storage in relatively small space, but also, by expansion, to effectively exhibit them as is worn on a human model.

A more particular object of the invention lies in the provision of a hanger in the form of a flexible envelope which may be selectively collapsed to lie flat or expanded to a three dimensional curved shape which simulates a part of the human body. The invention lends itself readily to the simulation of all or any of a relatively large number of parts of the body, such as the shoulders, the chest or bust, the waist and the hips.

A further object of the invention lies in the provision of a garment hanger having a collapsible and expandible body-forming envelope, and simple mechanism within the envelope for expanding and collapsing the envelope.

Still another object of the invention lies in the provision of an expandible garment hanger in which the mechanism for expanding the hanger is self-locking in its expanded state until manually released and which, when released, is collapsed by the internal stresses in the expanded envelope itself.

A still further object of the invention lies in 55 and

2

the provision of an expandible garment display form having a stretchable area expandible to a greater degree than the adjacent area so that a body may be closely simulated even to the inclusion of pronounced body protuberances such as the female breasts.

Another object of the invention lies in the provision of an expandible garment display form employing a flexible, body-forming envelope of 10 separate parts and part extensions, each extension line being hinged to an edge of the adjacent envelope part and pairs of extensions being hinged together so as to form, when expanded, fuller and more naturally curved body portions as required, for example, at the shoulders or sides of the human form.

These objectives and such other objects, features and advantages as may hereinafter appear or be pointed out, are achieved in the manner 20 illustrated by certain preferred embodiments shown in the attached drawings, in which:

Figure 1 is a rear elevation of a collapsed garment display form constructed in accordance with this invention;

Figure 2 is an enlarged fragmentary, cross-sectional view taken on line 2—2 of Fig. 1;

Figure 3 is a side elevation of the hanger hook taken in the direction of line 3—3 of Fig. 1;

Figure 4 is a side elevation of the garment display form of Figure 1, when in expanded condition;

Figure 5 is a front elevation of the expanded display device showing only the uppermost portion;

Figure 6 is an elevation of a hinge pivot member or hinge axis employed in the garment display form;

Figure 7 is an elevational view, similar to Figure 1, of a modified display form suitable for exhibiting skirts and the like;

Figure 8 is a fragmentary cross-sectional view taken along line 8—8 of Fig. 7;

Figure 9 is an elevation of the skirt display form of Figure 7 shown in expanded condition;

Figure 10 is a side elevation of the expanded skirt display hanger form;

Figure 11 is a cross-section taken on line 11—11 of Fig. 9;

Figure 12 is a front elevation of a modified display form suitable for exhibit of blouses or brassières;

Figure 13 is a top plan view of the device of Figure 12 shown in expanded condition;

Figure 14 is an enlarged elevation of a bust portion of the display form shown in Figure 12;

Figure 15 is an enlarged cross-section taken on line 15-15 of Fig. 12.

Referring to the drawings, numeral 10 generally designates a hanger similar to the bar or rod hangers of conventional type. Such a hanger supports an article of apparel in relatively flat condition. The hanger may be formed of wood, plastic, metal or other suitable material. It preferably includes a center piece 11 in which a hook 12 is rotatably secured. The hook may be formed of wire, and it is provided with a latching stud 13 (see Fig. 3) formed by welding or otherwise securing a rod-like element in a loop thereof. The function of latch 13 will herein-after be explained.

Rigidly embedded in or otherwise secured to the center piece 11 are two rod-like shoulder elements 14 each of which is headed on its outer end as at 15. Elements 14 are preferably made of wire and act as hinge pivot support members for the expandible envelope or form now to be described.

The body-forming envelope, generally indicated by reference numeral 20, is composed of relatively thin and resilient flexible sheet material such as plastic, fibre, metal, rubberized cloth, or the like, which may be stretched or expanded to body-simulating contour and which is capable of collapsing back to its initially flat condition by reason of the internal stresses in the material.

In Fig. 1 envelope 20 is shown as comprised of a front sheet 21 and rear sheet 22, each of which is provided with a plurality of longitudinally extending slits 23 for the purpose of increasing the flexibility so as to permit bending to a three-dimensional curved shape. At the upper part of the envelope, the sheets are preferably provided at each side with a pair of front and rear shoulder extensions 24. Each extension 24 is formed on one side with hinge leaves 25 which interfit with similar leaves 26 on the adjacent edge of the front or rear sheet 21 or 22. Similar leaves 27 on the opposite side of the extension interfit with the corresponding leaves 27 of the other extension of the shoulder forming pair. The hinge leaves 27 are slideably secured about one or the other of the hanger rods 14 and prevented from slipping off by the rod heads 15. Each of the hinge leaves 25 and 26 jointly receives a pivot pin 28. Thus each member 24 of each pair of shoulder extensions is pivoted to the other on rod 14 and also hingedly secured to the front or back sheet 21 or 22 on a pivot axis 28.

Along their side edges, sheets 21 and 22 are provided with two pairs of side extensions 30, just above the waist line. Below this level are two pairs of hip extensions 31. These extensions are hinged together in pairs and the extensions of each pair are hingedly secured to the front and rear sheets of the envelope in a manner similar to that explained in connection with the shoulder extensions. The side and hip extensions are, however, different in shape so as to cooperate with the front and rear sheets in defining a body-simulating contour. The separate side and hip extensions enable the use of uniform front and rear sheets, which may be cut from a relatively narrow sheet of plastic or other sheet material, to make forms of different sizes by simply varying the sizes of the extension pieces.

The pivot members for all the hinged connections are designated by numeral 28. They differ in length in accordance with the hinge length requirement of each location. While these pins may be solid rods, it will be readily understood that they may be formed of any material suitable

for use as a pivot pin or hinge axis, and it is desirable to use a somewhat flexible material. The pivot member 28 shown in Fig. 6 is, for example, shown to be a closely wound coil of spring wire, cut to the desired length. The end turns are shown deformed for permanent securement of member 28 in the hinge. At least one of these deformations would, of course, be formed after installation of the pivot member. Use of a flexible coil as a hinge pin or axis permits the body-forming sheets more readily to take their curved shapes when expanded, and therefore their use in the expanded envelope results in a form more closely simulating life-like proportions.

For expanding the display form, the envelope is provided, within its confines, with a pair of toggle-jointed members 35 and 36. These members are flat sheets of suitable, stiff material. Front sheet 35 is preferably wider than rear sheet 36 and is rounded to conform to body shape at its forward envelope engaging edge 37. The rear toggle member is similarly rounded at edge 38. Each of the rounded edges 37 and 38 is flexibly secured to the inner surface of the envelope front and rear sheets, respectively, by means of a hinge panel (39 and 40) and a hinge axis 28. Hinge panel 39 is preferably secured to sheet 21 at a higher level than that of hinge panel 40. The toggle joint securing the members 35 and 36 together is also preferably formed as a hinge, illustrated at 41, but this hinge is provided with a rigid pivot 42.

For moving the toggle joint or knee 41, there may be provided a rod-like operating member 45 having a hooked upper end 46 and a latching loop 47. The lower end of rod 45 is pivotally attached to the knee 41 of the toggle joint so as to raise the knee when hook 47 is elevated. This motion causes the toggle members 35 and 36 to move from a flat superposed position (illustrated in slightly spread condition in Fig. 2) to substantially aligned positions as shown in Fig. 4. During this movement outward pressure is applied to the envelope 20 by the rounded edges 37 and 38 of the toggle members. This forces the envelope front and rear sides outwardly, spreading them to an expanded body-simulating condition as illustrated in Fig. 4.

The outward spreading of the front and rear envelope sheets causes the side edges, which are secured together by the hip and side extensions, to pull inwardly and open the form into a substantially curved shape, while at the same time the shoulder extensions open and slide toward each other along rods 14. The opening of hinged extensions 24 results in a full, well rounded shoulder shape in the expanded form (see Fig. 4), and avoids formation of sharp, crease-forming shoulder edges. This is also true of the side and hip extensions.

The shape and positioning of the various extensions with respect to the front and rear sheets are such as to produce a pair of arm openings 48, and smaller openings 49 at waist level, and to increase the size of the chest and pinch in the waist, thus heightening the life-like proportions of the display device. The fully expanded envelope is a well-rounded form having full shoulders, an expanded chest or bust, a pinched-in waist and rounded hips extending outwardly below the waist line. It is apparent that such a form will attractively support and exhibit a garment nearly as well as if worn by a live model.

It will be observed in Fig. 4 that the toggle members 35 and 36 which have been moved into

alignment, or slightly beyond, by elevation of the rod 45 and toggle knee 41, are selflocked in such position by the resilient pressure of the expanded envelope. However as an added latching feature the rod loop 47 may be hooked around stud 13 on member 12 to prevent accidental downward movement of rod 45.

When it is desired to collapse the form, the rod 45 is unlatched from 13 and moved downwardly to lower the toggle knee 41. This movement will be aided by the pressure of the envelope walls 21 and 22, so that the device quickly collapses to its initial flat form as illustrated in Fig. 1.

Referring to Figs. 7 through 11 there are shown several views of a modified garment support suitable for displaying a skirt or the like. In this device the bar hanger is designated 50, and is centrally provided with a hook 51 and a latching aperture 52. The lower open portion of the bar 50 is traversed by a straight rod 53 which slideably supports the envelope.

In the modified device the envelope is formed of only two sheets, a front sheet 55 and a rear sheet 56, each of a height corresponding to that between the waistline and the hipline. The sheets are hingedly secured together at each side by means of hinge pins 57 formed of wire and having looped upper ends 58 extending above the sheets and slideably supported by rod 53. Sheets 55 and 56 are slit at 59 to lend flexibility, and the hinge pins 57 extend at an angle so that the envelope will open to a form having a smaller diameter at the waistline than at the hipline.

Toggle members 60 and 61 are provided between front and rear sheets 55 and 56. These are toggle-jointed at 62 by means of hinge pin 63 which initially is positioned above the ends of the toggle members which are secured to the envelope. This latter securement is accomplished by means of hinge panels 64 and 65 and hinge pins 28 similar to those previously described in Figs. 1 and 2.

An operating rod 66 is pivotally secured to the toggle knee, centrally of the toggle members, as illustrated at 67 in Fig. 11. The rod is initially disposed at an angle, extending toward one end of support rod 53 over which it is slideably looped. The upper end of the operating rod is bent to form a latching projection 69. When the upper end of rod 66 is grasped between loop 68 and projection 69 it may be slideably moved along and toward the center of support rod 53. Such movement will depress the toggle knee 63 and spread the envelope side walls 55 and 56 into a rounded form simulating the portion of the body between waist and hips. During the opening movement hinge pins 57 slide along the support rod 53 toward each other as shown in Fig. 9 and tend to somewhat constrict the waist line. The form may be latched in open position by inserting projection 69 of the operating rod into latching recess 52. To collapse the display form it is only necessary to release projection 69 and start moving the rod along support 53 to raise the knee of the toggle. As soon as the toggle members are out of alignment the envelope walls will force them toward parallelism and the form will resume its initial collapsed condition.

Another modified display form is illustrated in Figs. 12-14. This form is similar to that shown in Fig. 1 except that the lower hip portions and side extensions are omitted, leaving the form suitable for display of articles such as blouses, brassières and the like. In this form the hanger 12 including shoulder rods 14, together with the envelope 75

shoulder extensions, may be substantially identical with those described and shown in Fig. 1. The envelope comprises a front sheet 70 and a rear sheet 71 which, when flattened, curves downwardly and outwardly at 73 to provide arm openings and a chest or bust line in the expanded form. Below the widest portion, the sheet edges are angled inwardly and downwardly to a waist level and along these edges the sheets are hinged together by means of hinge pins 74.

To create a more life-like effect the envelope is provided with stretchable bust forming areas indicated generally at 75. This may be done in several ways, as by inclusion of patches of inherently stretchable material or by the provision of cuts or slits in the envelope wall which enable expansion to the desired shape. Fig. 14 is an enlarged view of one such pattern of slits suitable for creating, when expanded, a life-like breast contour. It will be observed that in this preferred embodiment the sheet 70 is provided with a series of interrupted cuts or slits 76 which define a center disc 77 surrounded by concentric rings 78, 79, 80 and 81. Each of these parts is connected to the adjacent ring, or to sheet 70, by flexible strips 84 at spaced points corresponding to the aforesaid interruptions. The strips are formed by additional cuts designated 82 and 83 which define small segments of rings included within each concentric ring and which permit extension of the rings from the plane of sheet 70, whether in flat or curved condition, to protruding positions as shown in Fig. 13. When collapsed the rings and connecting strips fold back into the flat plane of sheet 70.

For expanding the form and protruding the bust areas, a pair of toggle jointed members 90 and 91 and an actuating rod 45 may be employed. The rear member 90 is secured to the forward member 91 by a hinged toggle joint 92 having a pivot pin 93. Member 90 is hingedly secured to sheet 71 by means of hinge plate 94 and hinge pin 95. Member 91 is preferably formed with a pair of generally triangular protuberances 96. The apex of each part 96 is hingedly secured to the inner surface of a center disc 77 by a short hinge plate 97 and a short hinge pin 98, as best shown in Fig. 15. Member 91 is also formed with relatively short curved edges 99 and 100 adjacent to the triangular projections 96 which press the envelope front wall 70 outwardly so as to simulate body curvature.

It will be noted that lifting of operating rod 45 elevates the toggle joint and expands the envelope to body conforming shape while at the same time projections 96 of the front toggle member stretch the bust areas 75 outwardly to protruding condition relative to the adjacent curved front surface 79. Upon release and lowering of the rod 45, the envelope, including the bust areas, collapses into a flattened condition.

To operate any of the display forms illustrated, a garment such as a dress, blouse, skirt or coat is draped over the hanger and hung therefrom in the usual manner. A large number of articles to be displayed may be hung in this way in a relatively small space. When it is desired to exhibit a particular article, the hanger may be removed from the rack in the storage space and the operating rod lifted or otherwise moved, as previously described, to expand the envelope into body-simulating form. The expansion of the form will fill out the article of apparel and effectively display it as if worn on a live model. When the garment has been adequately exhib-

ited, the operating rod is unlatched or moved to collapse the form. The garment and form will resume their initial flat condition and may again be stored in the restricted space.

It is apparent that the described display forms fulfill a need for a garment display device which may be readily collapsed or expanded, and which when expanded produces a well rounded full figure including shoulders, bust, back, waist and hips which closely approach actual body proportions and contours.

It will be understood that those skilled in the art may make modifications in the shape, size and details of the exemplified embodiments without necessarily departing from the scope and spirit of the appended claims.

Having described my invention and illustrated its use, what is claimed to be new and sought to be protected by grant of Letters Patent is:

1. A display device for supporting an article of wearing apparel comprising a bar hanger, a pair of flexible body-forming sheets supported thereon and secured together along portions of their side edges, a pair of members between said sheets and secured together in a toggle joint, the unsecured ends of said members being flexibly connected to said sheets, and a rod for moving said toggle joint to apply outward pressure upon said sheets to spread them from a flat collapsed condition in the plane of the bar to a curved body-simulating condition extending laterally of said plane.

2. A garment display device as set forth in claim 1 wherein each of said toggle jointed members is flat and provided with a convexly rounded edge, said rounded edges being the ones which are flexibly secured to said body-forming sheets.

3. A garment display device as set forth in claim 1 wherein said toggle jointed members are of different size and are hingedly secured to the body-forming sheets at different levels whereby the expanded body-forming sheets are spread in varying degree by said toggle jointed members.

4. A garment display device as set forth in claim 1 wherein said body forming sheets are formed with support areas slideably hinged to said bar hanger, whereby movement of the jointed members to spread said sheets causes said support areas to slide toward each other along said hanger.

5. A garment display device constructed as set forth in claim 1 wherein said body-forming sheets are resiliently flexible and inherently tend to return to flattened condition, and said toggle jointed members are movable by said rod to a self-locking position in which the members have moved through and slightly beyond a plane of alignment so that the body-forming sheets are locked in spread body-simulating form notwithstanding the collapsing force inherent in the resiliency of said sheets.

6. A garment display device constructed as set forth in claim 1 wherein said bar hanger and said rod for moving the toggle joint are provided with cooperating means for latching the joint in a sheet spreading position.

7. A display device for supporting wearing apparel, comprising a body-forming flexible envelope, said envelope being formed of front and rear flat sheet members and means securing them together along side edge portions thereof, said securing means including a pair of flat lateral extensions of said members hinged together, each extension being also separately hinged to the corresponding one of said members, and means

on the inside of said envelope for spreading said sheet members apart to expand said envelope to body-simulating form.

8. A display device for supporting wearing apparel comprising a normally collapsed body-forming flexible envelope expandable to a curved body-simulating form, said envelope being formed of front and rear sheets, and hinges for securing these sheets along side edge portions thereof, said hinges comprising flexible pivot members formed of closely coiled wire springs, said pivot members being adapted to flex laterally upon expansion of said envelope.

9. A supporting and display device for wearing apparel comprising a bar hanger, a body-forming flexible envelope supported on the bar and normally collapsed into flat overlying sheets in the plane of the bar, means within the envelope for expanding the envelope to a curved body-simulating form extending laterally of said plane, a portion of said envelope being stretchable from a flat sheet to an expanded condition in which it projects beyond the contour of the adjacent envelope area to simulate a body protuberance, and means associated with said first-named means for expanding said stretchable portion to its projecting condition when said envelope is being expanded.

10. A display device as set forth in claim 9 wherein said stretchable portion of the envelope includes a slotted area to permit expansion to a protruding condition.

11. A display device as set forth in claim 9 wherein said stretchable portion of the envelope is formed by a series of concentric rings separated from each other by slits and each connected to the adjacent ring by a plurality of flexible strips.

12. A display device as set forth in claim 9 wherein said means for expanding the envelope and its stretchable portion comprise a pair of toggle jointed members flexibly secured to the envelope, each of said members having an envelope engaging edge and a protrusion from one of said edges in engagement with the stretchable portion of the envelope for expanding said portion to its projecting condition.

13. A supporting and display device for wearing apparel comprising a bar hanger, a flexible body-forming envelope supported thereon and normally collapsed into flat overlying sheets in the plane thereof, said envelope being shaped to provide, when expanded laterally of said plane, a rounded body-simulating form comprising shoulders, back, chest, waist and hips, the shoulder and side portions of the envelope adjacent the waist being formed by pairs of extension members, each pair hinged together and each member being separately hinged to a corresponding edge of the envelope, a pair of toggle jointed flat elements hingedly secured to the envelope and disposed flatwise between said overlying sheets in the collapsed condition of the envelope, and an operating member attached to the toggle joint of the elements for moving the joint to apply outward pressure on said envelope to expand it to body-simulating form.

14. A display device for supporting an article of wearing apparel, comprising a pair of flexible body-forming sheets secured together along portions of their side edges, a pair of members between said sheets and secured together in a toggle joint, the outer ends of said members being flexibly connected to said sheets, and an actuating member articulated to said toggle joint in the hinged region thereof for moving said toggle

joint to apply outward pressure upon said sheets to spread them from a flat collapsed condition to a curved body-simulating condition.

15. A display device for supporting wearing apparel, comprising a normally collapsed body-forming envelope composed of flexible flat overlying sheets hingedly connected at their side edges, and a collapsible spreading instrumentality on the inside of said envelope for pressing outwardly upon said sheets to spread them apart and deform them in the regions between said hingedly connected side edges in a generally convex outward direction thereby expanding the envelope to a curved body-simulating form, said collapsible spreading instrumentality comprising

a pair of articulated spreadable members selectively actuatable to effect expansion or collapse of said body-forming envelope.
